HAIR CURLER

Nathan L. Solomon, Englewood, N. J.

Application July 5, 1949, Serial No. 102,977

4 Claims. (Cl. 132—42)

1

This invention relates to curlers and particularly to resilient curlers which may be used comfortably by a person while sleeping, and which are readily adaptable for both large and small curls.

Soft or resilient curlers have been proposed in the past. However most of such curlers heretofore proposed were either in the form of substantially solid fibrous core members which adversely absorbed and retained moisture for a long time and thereby delayed completing the curl; or, solid or tubular plastic material which impeded curl drying ventilation.

Objects of the invention include providing: a highly resilient curler which may be slept upon with ease; a resilient curler which has good shape retaining and/or returning characteristics; a curler which has better ventilating and curl drying characteristics than curlers heretofore proposed; economical and highly efficient manufacturing possibilities.

Features of the invention include the development of a curler or curlers wherein: the main body section is made of inexpensive highly resilient coiled wire; a soft tape-like member to lock the swatch of hair curled upon the main body at the start and/or at the completion of the curling; structure which provides wide air circulation for quick drying; divers locking points so that both large and/or small curls may be securely maintained thereon.

Other objects, features, and advantages will be apparent hereinafter.

In the drawings which show the present preferred embodiment of the invention:

Fig. 1 is a plain end view of the main body member of the present invention.

Fig. 2 is a side view of the complete present preferred form of the present invention, in unloaded condition.

Fig. 3 is a side sectional view, as on line 3—3 of Fig. 1, of the curler shown in Figs. 1 and 2, but in loaded condition.

Fig. 4 is a fragmentary sectional view, similar to Fig. 3, but showing the main body yielding and partially collapsed.

Fig. 5 shows a slightly modified form of the present invention.

Fig. 6 is a central fragmentary section of Fig. 1 and shows the present preferred final locking means. Fig. 7 discloses a slightly modified form of the curler shown in Figs. 1—4.

Referring now in detail to the drawings, and first to Figs. 1, 2, 3, 4 and 6 which show the present preferred embodiment of the invention, a main body 10 is formed by making a spirally wound

2

coil, of wire or other resilient material, in the desired diameter and length. For example, small diameter short length coils are provided for small curlers and vice versa for large curlers.

However, as will be pointed out in greater detail hereinafter, long curlers of the present invention may be used advantageously to make small curls as well as large ones.

This main body 10 is preferably made with 10 uniform spaces 11 between each spiral wound coil 12 to provide good resiliency and to cooperate in locking the curl. For purpose of illustrating the present invention the coils are shown as rather large diameter wire but in actual use .010 to .020 diameter wire seems to work out very well. This coiled main body 10 provides a core upon which a swatch of hair may be wound or curled. Surprisingly the hair does not slip down in between the coils, because the many filaments 20 of hair in the swatch crisscross each other so frequently that the swatch acts like a band and covers many of the coils. Both ends of the coil are preferably given return bends 13 inwardly as may be seen best in Figs. 1, 2, and 3 to prevent the ends from hooking into the hair.

To lock the swatch of hair before and/or after curling, the present invention in its preferred form (Figs. 1—4 inclusive and Fig. 6) includes a tape 14 having inner and outer loops 15 and 16 respectively extending longitudinally of the coils with a knot 17 at one end of the coil, preferably cast at least once about the last coil and having one free end section 18 of slightly greater length than the main body to form a lock, said 30 knot 17 being of any conventional form which will not open when the free end section 18 thereof is pulled.

Thus, to use the present curler a user may start the outer end 19 (Fig. 4) of a swatch of hair under loop 16, or between loop 16 and main body 10 and thereafter wind the swatch completely upon the exterior of the main body whereupon it is merely necessary to cast the outer free end section tautly over the curl and 40 into one of the closest spaces between coils (Figs. 2 and 6) where said coils firmly grip and hold the free section 18 (Fig. 3).

Advantageously, if a swatch is relatively small and only half covers the main body 10, it is possible to pass the free end section 18 between coils near the center section longitudinally of the main body and thereby tautly hold a small curl as well as a large curl, something not possible with many curlers wherein a swingable 50 wire lock or the like is used.

The curler so far described is very comfortable

for the user. For example, a girl can go to bed with her hair put up on a number of these curlers yet if her head rests upon several of them they yield readily as may be seen best in Fig. 4.

For economy it may be preferable to make the main body 10' as shown in Fig. 5 modification wherein the ends are merely close wound, to avoid the more difficult and more costly return bend type structure of Figs. 1 through 3. The tape locking means for this main body 10' may be the same and function the same as that shown in Figs. 2, 3, 4, and 6.

Fig. 7 discloses another slightly modified form of the present invention wherein the locking means includes only a single strand 21 suitably knotted as at 22, so that much less tape need be used and so that assembly of the tape to the main body can be more easily effected. With this form it is merely necessary to curl a swatch of hair onto the main body 10 (or 10') then take the single strand section 21 and force it between the desired coils.

The above described curlers are very advantageous for resting and/or for sleeping because the coils are highly resilient and tend to yield or conform with head shape and with irregularities of a pillow or the like. (See Fig. 4.) Conversely they also have excellent shape returning characteristics.

In use, a person normally wets the swatch of hair as by dipping a comb in water or hair setting solution then pulling the wet comb through the swatch, whereupon the wet swatch is curled on the body 10, or 10', and the locking tape sections 18 or 21 is pulled tight over the curl and snug between a suitable pair of adjacent coils e. g. between coils near the end of the curler body when a large swatch is wound or curled thereon, as shown in Fig. 3, or, away from the end, as shown in fragmentary Fig. 6, if a small curl is wound thereon. The wide spaces between the coils and the large open center coil greatly facilitate and speed up the curl setting which occurs by reason of the hair drying in the curled shape.

To remove the curler it is merely necessary to pull the tape from between the coils of the main body whereupon the curl opens slightly and the entire main body can be pulled longitudinally therefrom.

Variations and modifications may be made within the scope of this invention and portions of the improvements may be made without others.

Having thus fully described the invention, what is claimed as new and for which it is desired to secure Letters Patent is:

1. In a curler the combination of an elongated,

round, open coil body, a flexible strand looped around a longitudinal portion of said body, and said strand having a free section longer than said body and the end portion of which is adapted to be wedged between coils of said body.

2. A curler comprising an elongated open spirally coiled body, a flexible strand looped around a longitudinal portion of said body from one end coil to the opposed end coil, means securing the looped strand to one end coil of said body, and said strand having beyond said means a free section adapted to be cast over said body and to be secured between divers coils thereof.

3. A curler comprising an elongated open spirally coiled body, a flexible strand looped around a longitudinal portion of said body from one end coil to the opposed end coil, means securing the looped strand to one end coil of said body, said strand having beyond said means a free section adapted to be cast over said body and to be secured between divers coils thereof, said free section of the strand being longer than said body, and said means comprising a knot fixed to said end coil.

4. A curler comprising an elongated open spirally coiled body, the coil of said body being composed of light wire forming a readily flexible body, end coils of said body extending into and longitudinally of said body, an elongated flexible strand looped around a longitudinal wall portion of said body around end coils, means fixing the loop of said strand to one of said end coils, and said strand having a free section of greater length than said body, the free end portion of which is adapted to be secured between predetermined adjacent coils of said body.
